(57) **CLAIM**

The ornamental design for a paint roller tray, as shown and described.

DESCRIPTION

FIG. 1 is a perspective view of a paint roller tray showing my new design, the cover shown in broken lines is environment and forms no part of the claimed design.

FIG. 2 shows a first end view of the paint roller tray of the present invention, highlighting the handle portion.

FIG. 3 shows a second end view of the paint roller tray of the present invention.

FIG. 4 shows a first side view of the paint roller tray of the present invention.

FIG. 5 shows a second side view of the paint roller tray of the present invention.

FIG. 6 shows a side view of the paint roller tray of the present invention supporting itself in an upright configuration from a level surface.

FIG. 7 shows an overhead view of the paint roller tray of the present invention; and,

FIG. 8 shows an underside view of the paint roller tray of the present invention.

The broken lines shown in the drawings represent environmental effects or potential embodiments and do not form any part of the claimed design.
